Primary Examiner — Elizabeth Albert(74) *Attorney, Agent, or Firm* — Gloria Tsui-Yip, Esq.; Wendi Opper Uzar, Esq.(57) **CLAIM**

The ornamental design for a removal tool, as shown and described.

DESCRIPTION

FIG. 1 is a right side elevation view of the removal tool showing my new design;

FIG. 2 is a left side elevation view thereof;

FIG. 3 is a front elevation view thereof;

FIG. 4 is a rear elevation view thereof;

FIG. 5 is a bottom plan view thereof;

FIG. 6 is a top plan view thereof; and,

FIG. 7 is a perspective view thereof.

The broken lines in FIGS. 1-7 are included for the purpose of portions of the writing instrument that form no part of the claimed design.

1 Claim, 4 Drawing Sheets*FIG. 1*
